UNITED STATES PATENT OFFICE.

CORNELIA E. GILBERT, OF NEW YORK, N. Y., ASSIGNOR TO THE PANTASOTE COMPANY, OF NEW YORK, N. Y., A CORPORATION OF WEST VIRGINIA.

DESIGN FOR A FABRIC.

42,416.

Specification for Design.

Patented Apr. 23, 1912.

Application filed December 22, 1911. Serial No. 667,418. Term of patent 14 years.

To all whom it may concern:

Be it known that I, CORNELIA E. GILBERT, a citizen of the United States, and resident of the borough of Manhattan, city, county, and State of New York, have invented a new, original, and ornamental Design for a Fabric, of which the following is a specification.

Reference is to be had to the accompanying drawing which illustrates in face view a section of a fabric showing my new design.

I claim—

The ornamental design for a fabric as shown.

CORNELIA E. GILBERT.
